UNITED STATES PATENT OFFICE.

ALOYSIUS C. LIPPERT AND ANTHONY A. HACKL, OF KENOSHA, WISCONSIN.

AUTOMOBILE RADIATOR CAP.

Application filed November 3, 1924. Serial No. 747,434.

To all whom it may concern:

Be it known that we, ALOYSIUS C. LIPPERT and ANTHONY A. HACKL, citizens of the United States, residing in Kenosha, in the county of Kenosha and State of Wisconsin, have invented a new and useful Improvement in Automobile Radiator Caps, of which the following is a specification.

This invention relates to closures for automobile radiators and the like and, while it has particular application to radiator caps of the general type shown in Patent No. 1,472,878, granted November 6, 1923, to Aloysius C. Lippert and John A. Sinko, it is not restricted to any particular construction, except as defined in the appended claims.

An important feature of the invention is the provision, in a radiator cap involving an outer body and an inner locking sleeve attachable to the radiator neck, of an inwardly extending rib, or bead, on said insert adapted to contact with the radiator neck when the insert is tightly screwed onto said neck to provide a seal preventing leakage of the water or steam from the radiator.

Another feature of the invention is the provision of sealing means, in a radiator cap construction of this character, which may be economically provided by practical manufacturing operations so that the cost of production may be kept relatively low.

A further important feature resides in the formation of the insert so that stock for threads therein is provided without expensive operations and with a uniform thickness of metal in the insert. Said insert, in accordance with the invention, is also conveniently formed to provide clearance between the threads and the sealing rib, or bead, above referred to, which will facilitate the attachment to the radiator neck in such manner as to provide an extremely tight sealing engagement, and this without entailing the additional expense of a separate operation to provide such clearance.

Numerous other objects and advantages of the invention will be apparent as it is better understood from the following description, which, taken in connection with the accompanying drawings, discloses a preferred embodiment thereof.

Referring to the drawings,

Figure 1 is a front elevation of a radiator cap in which the invention is embodied, the same being shown in position upon the filler

neck of a radiator and being partially broken away and sectionalized for convenience in illustration; and

Figs. 2 and 3 are horizontal sectional views, taken respectively upon the section lines 2—2 and 3—3 of Fig. 1.

In said drawings, we have shown, for illustrative purposes only, a preferred form of our invention, in which the reference character 11 indicates an outer body, having laterally extending arms 12 and being provided with a hinged cover 13, adapted to carry a motometer 14, or like device, a latch 15 being provided to hold said cover tightly to the body and in contact with a gasket 16, of rubber or like material, suitably positioned upon the interior of said body. An inserted locking member 17, of brass or like workable material, is disposed in a central opening 18 in said body and in the present instance is adapted to be locked to said body by means of integral projections 19, extending into a circular groove 21 formed on the interior of the cap body, it being apparent that with this construction, said body may be rotated relatively to the insert, but separation of the parts is prevented and the rotation of the body will not tend to remove said insert from the radiator neck. The insert is attached to said radiator neck 22 by means of threads 23, formed on the interior of the bottom portion of the insert, which portion is rolled inwardly, as indicated at 24, to provide stock for the threads.

Said insert is provided with an inwardly extending bead, or rib, 25 which may be formed by bending the material inwardly and exerting pressure upon the opposite ends of the insert to collapse the bead, as shown in Fig. 1 of the drawings. This operation may be performed in such manner as to provide a line of seal 26 inwardly from the outer edge of the radiator neck and to provide clearance, as shown at 27, above and about the outer portion of said radiator neck and above the threaded portion 23 of the insert. With this construction, said insert may be screwed down so as to draw the circumferential sealing portion 26 of said bead 25 tightly against the top of the neck 22, thus preventing leakage of the contents at this point. The gasket 16 is provided for preventing leakage at the top of the insert, or between the cover and body of the cap, so that the cap is leak-proof and thoroughly efficient in service.

For the purpose of screwing the cap onto the radiator, we employ a ratchet member 28, disposed in a recess 29 in the insert and having a projecting edge part 31 adapted to engage in recesses 32 formed in the outer cap body and engageable when said outer body is rotated in one direction only. One of the recesses 32 extends to the bottom of the outer body, as shown in Fig. 1, to facilitate the assembly of the body and insert with the ratchet member 28 in position, and it will be understood that the number of ratchets and of said recesses might be increased, if desired. We prefer, however, to provide said recesses at opposite sides of the cap, inwardly from the projecting arms 12, as shown in the drawings, since there is more stock in this area and the grooves are less likely to weaken the cap body.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

30 We claim:

1. A radiator cap for automobiles or the like, comprising a cap body having a central opening therein, and a bendable locking member attachable to the radiator neck and disposed in the central opening in said body, said locking member having a laterally rolled bead adapted to contact with the top of the radiator neck to prevent leakage.

2. A radiator cap for automobiles or the like, comprising a cap body having a central opening therein, and a bendable locking member attachable to the radiator neck and disposed in the central opening in said body, said locking member having a part bent outwardly therefrom and engaging in a circular groove formed on the interior of said body and also having a part bent laterally and adapted to contact with the top of the radiator neck to prevent leakage.

3. A radiator cap for automobiles or the like, comprising a body having a central opening therein, and an inserted locking member of bendable material disposed within said opening and attachable to the radiator neck, said member having integral projections bent outwardly therefrom and engaging in a circular groove on the interior of said body to prevent separation of the parts while permitting relative rotation of the body upon said member, said member also having a laterally rolled bead adapted to contact with the top of the radiator neck to prevent leakage.

4. A radiator cap for automobiles or the like, comprising an outer body having a cen-

tral opening therein, and an inserted locking member, of brass or like material, attachable to the radiator neck and having oppositely bent parts adapted respectively to lock said body thereto and to engage the top of the radiator neck to prevent leakage.

5. A radiator cap for automobiles or the like, comprising an outer body having a central opening therein, and an insert of bendable material disposed within the opening in said body and attachable to the radiator neck, said insert being adapted to be locked to said outer body and having a laterally rolled bead engageable with the top of the radiator neck to prevent leakage.

6. A radiator cap for automobiles or the like, comprising an outer body having a central opening therein, and an insert disposed within the opening in said body and attachable to the radiator neck, said insert being adapted to be locked to said outer body and having an inwardly extending collapsed bead engageable with the top of the radiator neck to prevent leakage and providing clearance beneath the outer part thereof whereby the insert may be threaded onto the radiator neck and drawn down to produce tight sealing engagement between said body and said neck.

7. A radiator cap for automobiles or the like, comprising an outer body having a central opening therein, and an insert of bendable material disposed within the opening in said body and attachable to the radiator neck, said insert being adapted to be locked to said outer body and having a laterally rolled bead engageable with the top of the radiator neck to prevent leakage, said insert being threaded beneath said bead to screw onto the radiator neck and clearance being provided between the threaded portion of the insert and the bead.

8. A radiator cap for automobiles or the like, comprising an outer body having a central opening therein, and an insert disposed within the opening in said body and attachable to the radiator neck, said insert being adapted to be locked to said outer body and having an inwardly extending bead engageable with the top of the radiator neck to prevent leakage and the insert being threaded beneath said bead, the material of the insert being rolled inwardly in the threaded area to provide stock for the threads.

9. In a radiator cap for automobiles or the like, the combination of an internal collar having an opening therethrough and having means for attachment to the radiator neck, an external collar fitting around said internal collar, and a pivoted closure for said external collar adapted to have a thermometer or the like permanently secured thereto, said outer collar having an interior circumferential groove and said inner collar

having an integral projection extending into said groove to prevent separation of the collars while permitting relative rotation of the outer collar, said inner collar having 5 also a laterally rolled bead adapted to contact with the top of the radiator neck to prevent leakage.

10. A radiator cap for automobiles or the like, comprising an outer body having an 10 opening therein, and an inserted locking member, of brass or like workable material, adapted for attachment to the radiator neck, said insert having a portion intermediate 15 its top and bottom edges bent laterally and adapted to cooperate with said radiator neck to form a seal preventing leakage of the contents of the radiator.

11. A radiator cap for automobiles or the like, comprising an outer body having an 20 opening therein, and an inserted locking member, of brass or like workable material, adapted for attachment to the radiator neck, said insert having a portion intermediate 25 its top and bottom edges bent laterally and adapted to cooperate with said radiator neck to form a seal preventing leakage of the contents of the radiator and also having an outwardly projecting portion cooperating 30 with a groove in said outer body to lock said body and insert against separation while permitting relative rotation of the body.

12. A radiator cap for automobiles or the like, comprising an outer body having an

opening therein and being provided with a 35 pivoted closure adapted to carry a motometer or like device, an inner sleeve of bendable material and having means for attachment to the radiator neck and means for locking to said outer body, said sleeve having 40 a laterally bent portion adapted to be arranged in sealing engagement with the radiator neck.

13. A radiator cap for automobiles or the like, comprising an outer body having an 45 opening therein, an inner sleeve of bendable material and having means for attachment to the radiator neck, and means for locking to said outer body, said sleeve having 50 a laterally bent portion adapted to be arranged in sealing engagement with the radiator neck.

14. A radiator cap for automobiles or the like, comprising an outer body having an opening therethrough, a closure pivoted to 55 said body, an inserted locking member of bendable material disposed in the opening of said body, and a gasket within the body at the top preventing leakage between the body and cover and between the body and 60 inserted member, said inserted member having means for attachment to the radiator neck and being provided with a laterally bent sealing portion adapted to contact with the radiator neck to prevent leakage between 65 said insert and neck.

ALOYSIUS C. LIPPERT.
ANTHONY A. HACKL.
